UNITED STATES PATENT OFFICE.

ALBERT F. SCHIFFLING, OF INDIANAPOLIS, INDIANA.

BURGLAR-ALARM.

SPECIFICATION forming part of Letters Patent No. 758,389, dated April 26, 1904.

Application filed December 3, 1903. Serial No. 183,658. (No model.)

To all whom it may concern:

Be it known that I, ALBERT F. SCHIFFLING, a citizen of the United States, residing at Indianapolis, in the county of Marion and State 5 of Indiana, have invented certain new and useful Improvements in Burglar-Alarms, of which the following is a specification, reference being had therein to the accompanying drawings.

My invention relates to certain new and 10 useful improvements in burglar-alarms; and it consists in the mechanism adapted to be connected to door-knobs, so that when the door-knob is turned an alarm will be sounded for the purpose of attracting attention.

15 The object of this invention is to provide a means which when applied to a door-knob the slightest movement of the said knob will operate the mechanism to cause the alarm-bell to ring; also, to provide means whereby the 20 mechanism can be readily disconnected from the door-knob, so that an alarm be not made when it is not required, as during the daytime. I attain these objects by means of the mechanism illustrated in the accompanying 25 drawings, in which similar numerals of reference designate like parts.

Figure 1 is a broken view of a portion of a door looking at the interior side thereof and showing my invention of a burglar-alarm applied thereto. Fig. 2 is an end broken view of the same, partly in section. Fig. 3 is a broken view of a door, showing the push-button whereby an alarm may be made from the outside. Fig. 4 is an enlarged view of the 30 lever for operating the push-bar of the alarm-bell and looking in the direction of the arrow *a*. (See Fig. 5.) Fig. 5 is a side view of said bell looking in the direction of the arrow *b*. Fig. 6 is an enlarged sectional view of the 35 lever for operating the push-bar of the alarm-bell and looking in the direction of the arrow *a*. (See Fig. 5.) Fig. 7 is a side view of said bell looking in the direction of the arrow *c*. (See Fig. 6.) Fig. 8 is a diagram of the cam-rollers for operating the bell-lever and showing said rollers in their normal position, 40 and Fig. 9 is a similar diagram view showing one of the rollers in contact with the throw-out socket of the bell-lever to depress the latter.

A door 1 may be of the usual form of construction provided with the usual door-knobs

2, whereby the latch 3 is manually operated 50 to unlatch or disengage its catch to permit the door 1 to be opened. A clamp 4, carrying the cam-rollers 5 and 6, is adapted to encircle the shank 7 of the inner knob of the door to clamp same and retain the cam-rollers 5 and 6 55 in position to contact the sleeve 8 of the bell-operating lever 9. The bell-lever 9 is fulcrumed on its fulcrum-bracket 10, secured on the inner side of the door 1, and the forked end 11 of the said lever 9 is adapted to bear 60 against the push-bar 12 of the alarm-bell 13, so that when the sleeve 8 is engaged by either of the cam-rollers 5 or 6 the same is depressed at its end and the forked end 11 of said lever 9 is forced against the push-bar 12 to move 65 the same to release the bell-hammer mechanism to sound an alarm.

It is frequently necessary during the daytime that the alarm mechanism connected with the door-knob be disconnected, so that the 70 door may be opened and closed without causing an alarm. To accomplish this purpose, I construct the sleeve 8 in such a manner that the same may be quickly slid along the end of the lever 9 to move the same out of the 75 plane of contact of the cam-rollers 5 and 6 and be secured in such position, which element I will now proceed to describe.

The sleeve 8 is provided with a central bore 14, which is adapted to receive the end of the 80 lever 9 to fully slide thereon. A lock-pin 15 is secured in proper position on the lever 9, and the slot 16 is formed in the side of the said sleeve 8 and extends along a portion of its length, and said slot terminates at its end 85 in an engaging notch 17, so that when the said sleeve is raised by means of the handle 18, with its pin 15 in said slot 16, the sleeve is moved till the pin has reached the bottom of the latter, when by a slight turn of said sleeve 90 8 the notch 17 is caused to engage the pin 15, thereby holding the lower end of said sleeve above the plane of contact of the cam-rollers 5 and 6. When it is necessary to drop the sleeve 8 into position to be engaged by the 95 cam-rollers 5 and 6, all that is necessary to be done is to slightly turn the said sleeve 8 by means of its handle 18 to disengage the pin

15 from the notch 17 and permit the said sleeve 8 to fall by gravity into engaging position, as shown in Fig. 3.

Referring particularly to Fig. 2, it will be
 5 readily seen that an ordinary push-button alarm or annunciator may be used in connection with the above burglar-alarm mechanism. The push-button 19 is situated in position on the exterior of the door, and the said door is
 10 bored to receive the push-rod 20, which extends from the end of the push-button 19 and passes between the prongs of the forked end 11 of the lever 9 into the counterbore of the push-bar 12 of the alarm-bell, and thus when
 15 the said push-button is moved the push-bar 12 is moved a corresponding extent to cause the alarm-bell 13 to sound the alarm without in any manner interfering with the alarm mechanism connected to the knob 2 of the
 20 door.

The operation of this device will be readily understood from the following: Suppose the knob 2 is grasped by some one on the outside and turned to either the right or the left to
 25 cause either the cam-roller 5 or 6 to contact with the sleeve 8, the same will be depressed from its normal position, as shown in dotted lines, into the new position shown in full lines. (See Fig. 8.) This movement of the
 30 sleeve 8 causes the forked end 11 of the lever 9 to move the push-bar 12 of the alarm-bell 13 to release the bell-hammer, and thereby cause the latter to operate to sound an alarm. The operation is so simple and so self-evident
 35 from the drawings that further description is deemed unnecessary.

Having thus fully described this my invention, what I claim as new and useful, and desire to cover by Letters Patent of the United
 40 States therefor, is—

1. In an alarm, the combination with a door-bell having a projecting push-bar for releasing the ringing mechanism of said bell, of a cam adapted to be secured to a door-knob, a lever
 45 situated to extend from said door-knob to said push-bar of said bell and fulcrumed at a point intermediate its ends so as to move in a plane

at right angles with the plane of rotation of the knob of the door, said lever arranged to be operatively engaged by said cam on said door-knob and operatively connected to said push-bar.

2. In an alarm, the combination with a door-bell having a projecting push-bar for releasing the ringing mechanism of said bell, of a cam 55 adapted to be secured to a door-knob, a lever operatively connected at one end to said push-bar and at its opposite end to said cam, and an extensible piece on the cam end of said lever arranged to be moved into position to contact 60 said cams.

3. In an alarm, the combination with a door-bell having a projecting push-bar for releasing the ringing mechanism of said bell, a door-knob clamp, rollers pivotally mounted in said 65 clamp, a lever situated to extend from said door-knob to said push-bar of said bell, said lever provided with a forked end adapted to contact the end of said push-bar, and an extensible end said extensible end arranged to 70 be moved into position between said rollers to depress said extensible end of said lever when the door-knob is turned.

4. In an alarm, the combination with a door-bell having a projecting push-bar for releasing 75 the ringing mechanism of said bell, a door-knob clamp, rollers pivotally mounted on said clamp, a lever situated to extend from said door-knob to said push-bar of said bell, said lever provided with a fork adapted to contact 80 the projecting end of said push-bar, and having mounted on its opposite end an extensible sleeve, a sleeve - catch and a sliding sleeve mounted on said sleeve-receiving end of said lever, said sleeve provided with a longitudinally-extending slot as described substantially 85 and for the purpose set forth.

In testimony whereof I affix my signature in presence of two witnesses.

ALBERT F. SCHIFFLING.
